UNITED STATES PATENT OFFICE.

HENRY A. TRIPP AND WALTER TRIPP, OF EAST WILLIAMSON, NEW YORK.

FRUIT AND VEGETABLE PARER.

SPECIFICATION forming part of Letters Patent No. 259,842, dated June 13, 1882.

Application filed March 9, 1882. (No model.)

To all whom it may concern:

Be it known that we, HENRY A. TRIPP and WALTER TRIPP, citizens of the United States of America, residing at East Williamson, in the county of Wayne and State of New York, have invented certain new and useful Improvements in Fruit and Vegetable Parers; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

Figure 1 is a side elevation. Fig. 2 is a top view. Fig. 3 is an isometrical projection of part of the standard, showing the inclined planes for operating the knife and doffer. Fig. 4 is an isometrical projection of the doffer. Fig. 5 is a longitudinal section through the center of the head of the doffer. Fig. 6 is an end view of the head of the doffer. Fig. 7 is a plan of the paring-knife and adjustable gage. Fig. 8 is a vertical section taken on the line yy of Fig. 7. Fig. 9 is an isometrical projection of the gage.

Our invention relates more particularly to the construction of the head, whereby the guard is made adjustable, so as to take up the wear incident to use and grinding to maintain a straight edge, and to an improvement in the construction of the doffer, as will be hereinafter more fully set forth.

35 A represents a standard of any suitable construction, provided with means for securing it to a table or bench, an extension for sustaining a revolving table, D, said table carrying an arm, B, provided with a paring-knife, and an arm, C, carrying a doffer, and two sets of bearings for the shaft that carries the fork and the shaft that carries the pinion engaging with the gear of the revolving table D. The knife-arm B is set in bearings upon the revolving table 40 D, and is held in position by a coiled spring, and operated by a projection extending beneath the table and coming in contact with a properly-arranged inclined plane. Any other suitable construction may be used when desired.

45 The upper end of the arm B terminates in a head, E, provided with an oblong opening opposite the fork. In the side of the head pro-

jecting through the slot is placed the knife F, which is made adjustable by means of a screw, G, passing through the slot and into the head, 55 clamping the knife in place. In the upper side of the head and projecting through the slot is placed a guard, H, which is slotted in the center for adjustment, and secured to the head by a screw, I; or the guard may be secured ad- 60 justably in any convenient manner in a suitably-constructed head. This guard should be made of hardened steel, its purpose being to protect the head from wearing into an irregular form and to receive the wear upon its edge, 65 which may be kept straight by grinding and setting the guard forward so as to maintain the original position of the guard-edge, and thus maintain the original thickness of the paring.

The doffer-arm C is set in bearing-lugs on the 70 revolving table D, and is held back from contact with the contents of the fork, except when moved forward by the projection J, coming in contact with the inclined plane K, as the table revolves, which throws the doffer in and dislodges the contents of the fork. 75

In order to protect the fruit or vegetable on the fork from being bruised by friction, a cap or head, L, is pivoted on top of the doffer-arm C, and forms a freely-revolving head for contact with the article upon the fork, thus preventing any damage from friction. 80

We have shown our improvement in connection with a revolving table, but may use it with any other form of parer. 85

Having thus described our invention, we claim as new—

1. In an apple-parer, an adjustable guard for protecting the knife-head, constructed and arranged to be set up, after grinding, to maintain 90 an even thickness of paring, substantially as shown and described.

2. In a fruit or vegetable parer, a doffer provided with a revolving head for preventing bruises by friction, substantially as shown and 95 described.

In testimony whereof we affix our signatures in presence of two witnesses.

HENRY A. TRIPP.
WALTER TRIPP.

Witnesses:

E. W. KELLY,
JOHN W. MYERS.
